VENTILATOR FOR TRUCK COVERS

Wilbur F. Crawford, Waco, Tex.

Application August 4, 1937, Serial No. 157,406

5 Claims. (Cl. 98—13)

This invention relates to the art of ventilating and in particular to forced draft ventilation for the interiors of carrier vehicles employed in the transportation of passengers or merchandise in 5 which the load carrying portion is enclosed by a heavy fabric cover impervious to the passage of air and water.

It is well known that the forward motion of a vehicle of this character creates a strong suction at the rear end which not only constitutes a definite hindrance to the progress of the vehicle that is reflected in fuel consumption or power demand increase, but which sucks into the vehicle interior the highly toxic and deleterious exhaust 15 gases where the vehicle is propelled by an internal combustion engine. Also, road dust and dirt are sucked in, to the discomfort of passengers and to the actual detriment of merchandise or perishable goods susceptible to the harmful effects of such foreign matter.

An object of the present invention is to provide in an enclosed vehicle, ventilating means so related to the enclosing structure as to create under the influence of forward motion of the 25 vehicle a forced or positive rearwardly directed air draft throughout the vehicle interior, and which is released at the rear end thereof in a manner to eliminate the possibility of formation of a vacuum which could give rise to the aforementioned objectionable rear end suction.

Another object is to provide in a flexible truck body cover, ventilating means inherently capable of maintaining a passageway unobstructed to the free flow of air therethrough while at the same 35 time preventing the passage of rain, snow or sleet.

A further object is to provide a flexible cover for truck bodies and the like, having ventilating apertures provided with interior air current forming deflector means whereby to impart any desired directional air flow within the area encompassed by the cover when in service.

Other objects will be apparent from the description.

The present disclosure comprises an embodiment by which the invention is reduced to practice, and as the principles of the invention are capable of expression in various other structural arrangements it is to be understood that the invention may be practiced in any manner or form 50 not inconsistent with its scope as claimed.

In the drawing:—

Figure 1 is substantially a front elevation of a truck having a flexible cover equipped with the 55 invention.

Figure 2 is substantially a vertical longitudinal section therethrough, partly in elevation.

Figure 3 is an elevation of one of the ventilators as viewed from the interior of the cover.

Figure 4 is a section on the line 4—4 of Figure 3.

Figure 5 is a section on the line 5—5 of Figure 3.

The enclosed carrier vehicle 6, as here illustrated, comprises a truck having its body 10 behind the driver's compartment enclosed by a flexible fabric cover 7 of a known type, such as the "Dux-bak" produced by the Crawford-Austin Manufacturing Company, of Waco, Texas, waterproof and impervious to passage of air, mounted 15 on a known construction of frame 8 carried by the sideboards 9. With exception of the ventilating means to be described the cover and frame mount is, by way of example, the "Dux-bak dome" truck cover and frame manufactured by the hereinbefore stated Crawford-Austin Manufacturing Company.

As such covers when secured in position render the covered interior practically air-tight, there is no escape for the toxic, and sometimes 25 fatal, exhaust gas fumes sucked in under the rear flap 10, or for the dirt and dust, which objectionable entry arises by virtue of the rear end suction produced by the vacuum created behind the vehicle when in forward motion.

In order to break such vacuum and to insure proper ventilation within the covered body I provide the cover with ventilating means, preferably at a plurality of points, by which air is admitted to the interior and by which, when the vehicle is 35 in forward motion, the admitted air is passed as a forced draft from front to rear to discharge beneath the rear flap. Although not essential to proper functioning, it is preferred that the ventilators be located in the front wall 11 of the cover 40 as the air pressure is greater at the front than at any other point when the truck is in forward motion. Figure 1 illustrates the location of two such ventilating means having the general designation 12.

Each such ventilating means comprises a triangular aperture 13 cut in the cover by a V-shaped incision, the resultant flap 14 being in-folded along the triangle base 15 which provides one edge of the aperture, the flap being secured 50 by attachment to the cover wall inwardly of the line of fold, preferably by a line of stitching 16 parallel to and spaced from the line of fold comprising the base 15.

In order to prevent ravelling and for rein-

forcement, the edges constituting the sides 17 of the triangular aperture 13 and which converge to the apex 18 thereof are inturned and hem-stitched as at 19.

5 Cooperating with the aperture 13, and on the inner face of the cover wall portion, is a substantially semi-cylindrical conduit 20 arranged with its longitudinal axis perpendicular to and bisecting the base edge 15 of the aperture, the side edges 21 of the conduit being doubled inwardly for stiffening and being secured to the cover wall portion by lines of stitching 22.

10 The conduit 20 is so mounted that one end portion 23 thereof overlies the aperture 13, said 15 end portion being of somewhat rounded V-shaped form axially beyond the ends of the parallel side edges 21 with its tip 24 axially aligned with the aperture apex 18. At its other end the edge of the conduit is perpendicular to the side edges 21 20 and the material is doubled on itself and stitched to provide a marginal bead 25 which by virtue of its stiffening action assists in maintaining its semi-cylindrical cross-sectional form.

15 As shown best in Figure 3, the baffle end portion 23 is directed at an angle with respect to the cover wall portion, the converging end edges 26 and the tip 24 being doubled in and secured to the cover by lines of stitching 27. The material of the baffle end portion 23 is gathered in two 20 pleats 28 which extend inwardly from the edges 26 and converge in the axis of the conduit at a point substantially registering with the base 15 of the aperture 13. The pleats are secured by converging lines of stitching 29 and are held 25 flat by the expedient of doubly securing their outer ends beneath the lines of stitching 19 and 27. Thus, these flattened pleats 28 provide reinforcing means which maintain the end portion 23 substantially in a plane state as a stiffened closed end diverging from the cover wall 30 beyond the apex and side edges of the ventilating aperture, as illustrated in Figure 4, the juncture of the inner ends of the pleats and their combined 35 stiffening action having a pronounced ridging effect on the material of the conduit which effectively serves to maintain it against collapse 40 so that at all times the tubular passage remains open and unobstructed from end to end.

45 Although the conduit 20 may be constructed of any suitable material and be substantially inflexible in character, it is preferred that it be of the same material as the cover. The outlet end defined by the marginal bead 25 is spaced from the inlet end as defined by the aperture 13, the 50 extent of spacing being determined by the length of the conduit which, in all instances should be sufficient to place the inlet and outlet ends well out of registry transversely of the passage.

55 In the embodiment here illustrated the air 60 passage conduits 20 are vertically disposed on the inner face of the front wall 11 of the cover with the inlet apertures 13 being well below the outlet end portions 25 so that rain and sleet entering the apertures will be trapped by the baffle end portion 23 which by reason of its angled disposition is self-draining, and will thus be prevented from entering the interior of the covered body.

65 The ventilators are so arranged that the apertures 13 will be clear of the truck cab structure, so as to be unobstructed, and so that they will be spaced above the front end gate and clear of the frame bows in order that the conduits may maintain their tubular form at all 70 times.

75 It is a feature of the invention that the air conduits 20 inside the cover may be disposed in any desired manner as to direction and length whereby to position the air outlets at any desired points and thus insure a predetermined 5 directional flow of air through the area encompassed by the cover, the air pressure created by forward motion of the vehicle setting up a forced draft circulation.

80 In the illustrated embodiment the conduits 10 20 are directed to dispose their outlets at the upper front of the enclosed truck body, so that the fresh uncontaminated air enters along the top of the body under a constant pressure while the truck is in forward motion, discharging 15 downwardly and outwardly beneath the tail flap 10 in a continuous flow which effectively prevents the creation of a vacuum at the rear end of the truck, not only precluding the possibility of exhaust gas and dirt contaminated air entering the 20 enclosed interior but also decreasing power and fuel consumption by eliminating the drag of rear end suction.

85 If desired, covering flaps 30 may be provided on the exterior of the cover for substantially closing the apertures 13 when found desirable, as when travelling in sub-freezing weather or passing through the now frequently encountered dust storms. These flaps may be secured in open or closed position by suitable fastening means 30 34, such as turn buttons.

Having thus described the invention, what is claimed is:

1. In a flexible cover for truck bodies, interior 35 ventilating means comprising a substantially tubular flexible material conduit secured throughout its extent to the inner face of the cover, means reinforcing said conduit against collapse on the cover, said cover having an air inlet aperture in communication with an end of the 40 conduit, said conduit having an air outlet, and the end portion of said conduit adjacent said inlet aperture being angled relative thereto.

45 2. In a flexible cover for truck bodies, interior 50 ventilating means comprising a substantially rectangular length of flexible material edge fastened throughout its length to the inner 55 face of a portion of the cover and out of contact therewith except at the points of attachment, said cover having an air inlet aperture, one end of said length of material being gathered on itself and edge fastened to said cover around a portion only of said aperture, and the other end of said length of material being out of contact with said cover and provided with an air outlet spaced from said air inlet aperture.

60 3. In a flexible cover for truck bodies, interior 65 ventilating means comprising a flexible tubular conduit of substantially semi-cylindrical cross section secured along each side edge to the inner 70 face of the cover, said cover having an air inlet aperture adjacent one end of the conduit, said end of the conduit being edge fastened to the cover along the adjacent edge portion of said aperture, said conduit end also having a substantially plane portion transversely of the conduit and diverging from the cover directly behind said aperture, said substantially plane portion having stiffening means reinforcing it against collapse, and the other end of said conduit being 75 open and in spaced relation from said air inlet aperture.

4. In a flexible cover for truck bodies, a front 75 wall portion provided with an unobstructed air inlet aperture, an air deflecting baffle member 75

on the inner face of the cover behind said aperture and diverging therefrom, and said baffle member including a flexible conduit secured to the inner face of the cover around a portion of said aperture, and said conduit having an air outlet end spaced from said air inlet aperture baffle.

5. In a flexible cover for truck bodies, interior ventilating means comprising a flexible semi-

cylindrical tubular conduit secured on the inner face of the cover throughout each side edge and one end, said cover having an air inlet aperture opening laterally into said end of the conduit, the other end of the conduit being open, and said conduit having self-contained means preventing its collapse against the cover.
